UNITED STATES PATENT OFFICE.

FRANCIS E. SCHWENTLER, OF ST. LOUIS, MISSOURI, ASSIGNOR TO AMERICAN BRAKE COMPANY, OF ST. LOUIS, MISSOURI, A CORPORATION OF MISSOURI.

LOCOMOTIVE BRAKE-RIGGING.

1,138,253.

Specification of Letters Patent. Patented May 4, 1915.

Application filed September 16, 1914. Serial No. 861,972.

To all whom it may concern:

Be it known that I, FRANCIS E. SCHWENTLER, a citizen of the United States, and a resident of St. Louis, in the State of Missouri, have invented a certain new and useful Improvement in Locomotive Brake-Rigging, of which improvement the following is a specification.

This invention relates to brake rigging for driving wheels of locomotives, and particularly that type of rigging having two sets of rods and levers connected to the brake beams, one set at each side of the locomotive.

With the large capacity of brake cylinders now being used in the modern air brake equipment, it is sometimes difficult or impracticable to locate two brake cylinders side by side between the side frames of the locomotive, and the object of my invention 20 is to provide an improved construction in which a plurality of brake cylinders are located in tandem between the side frames, the pistons being connected by transverse equalizer bars and side rods with the respective brake beams at the side frames.

In the accompanying drawings: Figure 1 is a longitudinal section taken between the side frames of a locomotive with four pairs of driving wheels, and showing one form of 30 brake rigging embodying my improvement; Fig. 2, a plan of same, the side frames being indicated in dotted lines; and Fig. 3, a transverse section of the same.

In a brake design of this type, the brake shoes, S^1, S^2, S^3, S^4 , are mounted on the respective hangers, H^1, H^2, H^3, H^4 , supported on the respective side frames, and pivotally connected to the brake beams, B^1, B^2, B^3, B^4 .

The main brake levers, 5, are mounted at 40 each side frame upon the rock shaft, 6, and are connected by the usual pull rods, 7, 8, 9 and 10, and brake beam levers, L^1, L^2 , and L^3 , with the respective brake beams.

According to my improvement, a plurality 45 of brake cylinders, such as C^1, C^2 and C^3 ,

are horizontally located in tandem between the side frames, and supported on the respective cross frames, D^1, D^2, D^3 , the pistons being connected by the respective equalizer bars, E^1, E^2, E^3 , with the side pull rods, 11, 50 passing upon both sides of the brake cylinders, and attached at their ends to the respective brake levers, 5. By means of this simple construction, two or more brake cylinders may readily be installed in connection with almost any design of locomotive, for actuating the brake rigging without interfering with other parts of the locomotive construction. This design also has the advantage of being very flexible, as additional 55 cylinders may be applied, if desired.

Having now described my invention, what I claim as new and desire to secure by Letters Patent is:

1. In a locomotive brake rigging, the combination of brake levers, a plurality of horizontal brake cylinders located in tandem between the side frames of the locomotive, equalizer bars therefor, and pull rods connecting said equalizers with the brake levers. 65

2. In a locomotive brake rigging, the combination with the side frames, of a plurality of horizontal brake cylinders located in tandem between said frames, cross frames supporting said cylinders, equalizer bars for 75 said brake cylinders, pull rods connected thereto upon both sides of said cylinders, and brake levers actuated by said rods.

3. In a locomotive brake rigging, the combination of the side frames, a horizontal 80 brake cylinder located between said frames, an equalizer bar for said cylinder, pull rods connected to said equalizer upon both sides of said cylinder, and brake levers pivotally mounted on the side frames and connected to 85 said pull rods.

FRANCIS E. SCHWENTLER.
